UNITED STATES PATENT OFFICE.

STEWART R. MACE, OF MOULTON, IOWA.

DESIGN FOR A WATCH-CHAIN ATTACHMENT.

SPECIFICATION forming part of Design No. 11,668, dated March 2, 1880.

Application filed November 11, 1879. Term of patent 7 years.

To all whom it may concern:

Be it known that I, STEWART R. MACE, of Moulton, in the county of Appanoose and State of Iowa, have invented a new and Improved Design for Jewelry, of which the following is a specification.

The design is shown in the accompanying drawing, which represents a charm for watch-chains.

10 The design is intended for use with all articles of jewelry, such as pins, charms, badges, &c.; and it consists in the figure of a goat combined with any special emblem of any organization or society.

15 As represented, the goat is shown in connection with a chain of three links, upon which the goat stands.

The design may be produced in gold, silver, or other metal, or in combined metals in any color, as desired, and may also be applied to other articles of manufacture.

Having thus described my invention, I claim as new and desire to secure by Letters Patent—

The design for a jewelry-charm, consisting of 25 the figure of a goat, in connection with the series of chain-links or other society emblems, substantially as described, and shown in the accompanying illustration.

STEWART R. MACE.
